[57] CLAIM

The ornamental design for a paint dispenser with brush wipe and rest, as shown and described.

DESCRIPTION

FIG. 1 is a top, right side perspective view of a paint dispenser showing the design;

FIG. 2 is a top, right side perspective view of the paint dispenser according to FIG. 1, the broken-line disclosure of a person's hands holding the dispenser and a brush so as to wipe it across the cross bar are being shown for illustration purposes only and forming no part of the claimed design;

FIG. 3 is a top plan view of the paint dispenser;

FIG. 4 is a bottom view of the paint dispenser;

FIG. 5 is a front elevational view of the paint dispenser;

FIG. 6 is a rear elevational view of the paint dispenser;

FIG. 7 is a right side elevational view of the paint dispenser, the broken-line disclosure of a brush resting on the cross bar being shown for illustration purposes only and forming no part of the claimed design;

FIG. 8 is a left side elevational view of the paint dispenser; and,

FIG. 9 is a cross sectional view of the paint dispenser along line 9—9 of FIG. 3.
